UNITED STATES PATENT OFFICE

1,986,444

SPRAYING APPARATUS FOR LIQUIDS

Robert D. McIntosh, River Forest, Ill., assignor to
The Imperial Brass Manufacturing Company,
Chicago, Ill., a corporation of Illinois

Application December 17, 1931, Serial No. 581,602

4 Claims. (Cl. 299—89)

My invention is concerned with spraying apparatus for liquids, and is designed primarily to produce a device of the class described by which a stream of liquid only may be delivered, or by 5 which liquid commingled with compressed air to produce a mist of the liquid may be delivered.

It is further concerned with such an apparatus provided with a pressure regulator so that the force with which the liquid is delivered may be 10 regulated.

It is finally concerned with certain novel combinations of elements and details of construction, as will be hereinafter fully described and particularly pointed out in the claims.

15 To illustrate my invention, I annex hereto a sheet of drawings in which the same reference characters are used to designate identical parts in all the figures, of which,—

Fig. 1 is a side elevation of an apparatus containing my invention, with a portion of the tank broken away and in section;

Fig. 2 is a top plan view of the same with the hose detached; and

Fig. 3 is a vertical section, on an enlarged scale, 25 on the line 3—3 of Fig. 2.

The apparatus which I have illustrated as embodying the preferred form of my invention is designed primarily to distribute any desired liquid, which is placed in the body of the receptacle 10, the top 11, of course, having been removed by loosening the set screws 12 of the clamps 13 co-operating with the abutments 14 provided on the periphery of the cover for that purpose. The customary gasket 15 will be provided between the top of the receptacle and the cover.

Screwed into the top of the center of the cover, in the manner clearly shown in Fig. 3, is the member 16, which has threaded in one side 40 thereof the cock 17 attached to the hose 18, which delivers compressed air from any desired source. This cock 17 is thus connected to the passage 19, which opens into the vertically extending recess 20, the upper end of which has 45 screwed thereto the nut-like closure 21, which compresses against the annular shoulder 22 the gasket 23 which forms the valve seat for the valve 24, which has the stem 25 extending upward through an aperture in the closure 21, which also has the apertures 26 therethrough, so that the compressed air from the pipe 18 will 50 lift the diaphragm 27 having its edges secured between the top of the member 16 and the shoulder 28 formed on the interior of the cap casing 29 screwed thereon, as will be clearly seen in

Fig. 3. A helically-coiled expanding spring 30 in the recess 20 co-operates with the valve 24 to hold the same closed when the pressure within the chamber directly beneath the diaphragm 27 is high enough. When the pressure becomes too low, the helically-coiled expanding spring 31 in the cap member 29 co-operating with the disk 32 secured in the center of the diaphragm 27 depresses the diaphragm against the valve stem 25, opening the valve and allowing a fresh supply of the higher compressed air to enter the chamber containing the air under reduced pressure. The apparatus just described is a customary form of reducing valve, but I have improved the same in that I add to the screw 32', threaded into the top of the cap member 29 and serving to regulate the tension of the spring 31, and consequently the pressure of the reduced air, the handle 33 by which the receptacle may be conveniently transported.

The air under the reduced pressure passes through the bore 34, seen in dotted lines in Fig. 3, leading from the bottom of the chamber 35 beneath the diaphragm 27 into the tube 36 secured in the bottom of the member 16 and extending down to the bottom of the receptacle 10. As there might be a tendency for the air pressure to force the liquid back up through the tube 36 into the bore 34, I prevent this possibility by forming in the tube 36 one or more apertures 37, and I place in the tube 36, just above these apertures 37, the nipple 38, seen in dotted lines in Fig. 3, and the result is that the compressed air passing down through the tube 36, escaping from this nipple 38, prevents the possibility of any liquid being carried upward past the same.

The liquid in the receptacle 10 is delivered by the air pressure on top of it upward through the tube 39, which extends from the bottom of the receptacle and is secured in the bottom of the member 16, which has the bore 40 (seen mainly in dotted lines in Fig. 3) which opens into the edge of the bottom of the threaded recess 41 formed in the opposite side of the member 16 from the cock 17. This recess 41 has screwed into it the connection 42, which is of an inverted T-shape and has the passage 43 therethrough, the outer end of which passage is internally threaded, as seen at 44, to receive the threaded portion 45 of the needle valve 46, its outer end being closed 50 by the packing gland 47, and the valve 46 has secured on its outer end the handle 48 by which it is manipulated. The vertical arm 49 of the T-shaped connection 42 has the connecting nipple 50, seen in Fig. 1, threaded thereto and 55

connected by the hose 51 with the spraying nozzle 52, which is controlled by the hand-operated valve 53 in the customary manner. A bore 54 through the member 16 opens into the center of the bottom of the threaded recess 41, and this opening forms the valve seat for the needle valve 46.

The operation of the apparatus will now be apparent. If a solid stream of the liquid is to be discharged from the nozzle 52, the needle valve 46 is closed, and the liquid is forced by the air pressure in the receptacle 10 up through the tube 39, the bore 40 and the passage 43, out through the hose 51, and to the nozzle 52. The force of the liquid thus delivered can be regulated by adjusting the handle 33 to regulate the pressure of the air in the receptacle. If it is desired to deliver the liquid in the form of a mist, the needle valve 46 is opened and the compressed air rushing through the bore 54 and engaging the liquid in the passage 43 will mix with it so that it is delivered in the form of a mist from the nozzle 52. The amount of the air thus mixed with the liquid and the consequent fineness of the mist can be controlled by the extent to which the needle valve 46 is opened.

I preferably add to the member 16 a pressure gage 55 connected by the pipe 56 to the chamber 35, so that the operating pressure can be noted, and also a bleeder valve 57 likewise opening into the chamber 35, so that the pressure can be reduced to atmospheric, when desired.

While I have shown and described my invention as embodied in the form which I at present consider best adapted to carry out its purposes, it will be understood that it is capable of modification, and that I do not desire to be limited in the interpretation of the following claims except as may be necessitated by the state of the prior art.

What I claim as new, and desire to secure by Letters Patent of the United States, is:

1. In a device of the class described, the combination with a container, of a member adapted to be secured in one side of the container, and containing means for passing compressed air therethrough to the interior of the container, an outlet pipe from the bottom of the container into the member, an internally-threaded recess in the side of said member directly opposite to the compressed air inlet, a compressed-air outlet through said member terminating in a valve seat at the center of the bottom of the recess, an outlet

from the pipe through the member opening into the bottom of the recess, a connection screwed into the recess having an outlet in one side thereof, and a needle valve threaded into the connection and co-operating with the valve seat, for the purpose described. 5

2. In a spraying apparatus, the combination with a receptacle containing a liquid and closed by a head, of means for supplying air under pressure to the surface of said liquid, a pipe leading from the bottom of the receptacle to a discharge outlet, an air passage leading to said outlet from the upper part of the receptacle, an outlet member adapted to be secured in the head of the receptacle and connected to the aforesaid discharge outlet having a needle valve extending therethrough and co-operating with a valve seat in said head which terminates said air passage, a liquid passage in the head opening around said valve seat, and an outlet from the side of the member through which the liquid may be delivered unmixed with air when said valve is closed, or mixed with any desired quantity of air depending on how much the valve is opened. 10 15 20

3. In a device of the class described, the combination with a container, of a head, consisting of a lower part adapted to be screwed into the container and cup shape in the outer part, and an upper part screwed onto the top of the lower part, a diaphragm clamped between the two parts forming part of a pressure regulating valve, the valve member of which is located in the top of the lower part and co-operates with a valve seat in said lower part, a spring in the upper part co-operating with and engaging the diaphragm to regulate the pressure, a regulating screw threaded through the upper part and engaging the spring, an inlet passage leading to the under side of the valve seat, a passage from the cup to the container, an outlet terminating in a needle-valve seat, an outlet angle screwed into said outlet, a needle valve threaded through said angle and engaging the seat, a pipe opening into the bottom of the head, a passage through said head from the pipe to the outer side of the valve seat, 30 35 40 45 and an air passage through the head from the bottom to the inner side of the needle valve seat.

4. A device of the class described constructed as described in claim 3, in which the regulating screw has a handle on its outer end by which the container may be carried. 50

ROBERT D. McINTOSH.
